HAIR DRYER

Carroll M. Gantz, North Canton, Ohio, Robert H. Hose,
Mountainside, N.J., and Joseph T. Sestak, Canton, Ohio,
assignors to The Hoover Company, North Canton,
Ohio, a corporation of Delaware

Filed Jan. 15, 1968, Ser. No. 10,158

Term of patent 14 years

Int. Cl. D28—03

U.S. Cl. D86—10

Fig. 1

Fig. 2

Fig. 3

FIGURE 1 is a perspective view of a hair dryer embodying my new design with the hair drying hood in closed position;

FIGURE 2 is a side elevation view of the hair dryer in closed position;

FIGURE 3 is a front elevation view of the hair dryer in open position;

FIGURE 4 is a side elevation view of the hair dryer in open position;

FIGURE 5 is a top plan view taken along the section line 5—5 of FIGURE 4;

FIGURE 6 is a bottom view when viewed from below and taken along the section line 6—6 of FIGURE 4; and,

FIGURE 7 is a cross sectional view of the base member taken on line 7—7 of FIGURE 4.

We claim:

The ornamental design for a hair dryer, as shown.
